UNITED STATES PATENT OFFICE.

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

LOCOMOTIVE-STOKER.

1,277,352.

Specification of Letters Patent. Patented Sept. 3, 1918.

Application filed October 2, 1914. Serial No. 864,619.

To all whom it may concern:

Be it known that I, MAXWELL ALPERN, a citizen of the United States, residing in Philadelphia, Pennsylvania, have invented certain Improvements in Locomotive-Stokers, of which the following is a specification.

One object of my invention is to provide a stoker which shall be particularly adapted for feeding fuel to locomotive boilers, although it may be advantageously used in boilers of other types; it being also desired to provide novel means for causing a flow of fuel from the source of supply thereof to the point of discharge of the ashes.

Another object of my invention is to provide a stoker of the under feed type with a novel form of pusher mounted within the retorts, together with novel means whereby the amount of fuel moved by the pusher at each stroke may be varied at will.

I also desire to provide a stoker in which the retorts are of novel form and in which the areas of the active faces of the pushers, as well as the operative stroke thereof, may be conveniently adjusted to vary the rate at which fuel is caused to pass into the stoker.

The invention further contemplates novel means for governing the supply of air to the stoker.

These objects and other advantageous ends I secure as hereinafter set forth, reference being had to the accompanying drawings, in which,

Figure 1 is a vertical section taken centrally from front to rear through one of the retorts of a locomotive stoker constructed according to my invention;

Fig. 2 is a transverse vertical section taken on the line 2—2, Fig. 1.

Fig. 3 is a plan, partly in section, of the apparatus shown in Figs. 1 and 2;

Fig. 4 is an elevation of certain of the parts of the stoker.

In the above drawings, 1 represents a part of the inner shell and 2 a part of the outer shell of the boiler, which in the present instance is of the locomotive type, and has a fire door 3 opening into a fire box 4.

Extending across the bottom of said fire box adjacent the front or inner end thereof are a number of supporting bars 5 and 6, while across the rear of the boiler outside of the fire box extends a supporting structure of which a portion is indicated at 7 for carrying the rear of the stoker structure.

This latter includes a series of parallel wind boxes, on the tops of which are mounted twyters 8 each in the form of a hollow casting having air delivery openings 9 in its sides, and mounted to receive air from said wind boxes. Between each two adjacent boxes are spaces extending longitudinally of the stoker and forming retorts, which it will be noted decrease in depth from the rear to the front of the fire box.

While the top surfaces of the twyters all lie within a substantially horizontal plane, the bottoms of the retorts are inclined upwardly toward the front of the fire-box, being formed by reciprocating plates 11 having side flanges 11^a and slidably mounted on suitable guides provided on the stoker frame. These plates which constitute the floor portions of the side walls of the retorts, act as pushers, being each formed with a fixed shoulder or abutment 12 adjacent its rear end and having a suitable number of adjustable pusher abutments 13—14—15. These consist of angle plates pivoted to the pusher plate 11 so that their substantially vertical fuel engaging faces 20 project through openings in said plates as shown in Fig. 1.

Each pushing face is outwardly flanged at its lower end in order to limit its upward movement, and each of the abutments 13 has fixed to it or to its pivot a toothed segment 16 which in turn is connected by a link 17 to arms 18 and 19 respectively connected to the pusher plates 14—15. For adjusting the abutments 13, 14, 15, I provide a shaft 21 journaled in a bracket 22 and having a worm wheel 23 meshing with the teeth of the segment 16;—its outer end being provided with a hand wheel 24.

The rear of the stoker frame or casing is provided with a series of horizontal openings leading to the various retorts 10 and each of these has immediately below its inner end a dead plate 25 within the adjacent retort. The reciprocable pusher plate 11 is so supported that its front end is practically at the level of the twyters, with the result that each of the retorts varies in depth from a maximum adjacent the rear of the stoker to a minimum adjacent the innermost of the twyters 8. Between these latter twyters and the front end of the fire box is slidably mounted a series of reciprocable frame structures 26 each carrying any desired number of twyters 27 arranged in suitable stepped form 110

so that the lowermost projects farther toward the front of the fire-box than the twyer immediately above it.

The transverse frame member 26 carries a suitable number of brackets 28 in which is journaled a shaft 29 having fixed to it a transversely extending grate 30 which when in its horizontal position, practically closes the space between the last of the twyers 27 and the adjacent front wall of the fire box. By turning said shaft, however, this grate may be swung down through any desired angle to or toward a vertical position and for this purpose I key upon it a toothed segment 31 actuated from a shaft 33 through a worm 32. This latter is journaled in a bracket 34 carried by the frame member 6 and its outer end is carried in a bearing provided on a bracket 35, there being a hand wheel 36 fixed to its outer extremity.

For supplying fuel to the retorts I mount at the rear of the stoker a series of hoppers 37, 38, 39, 40, all communicating with a single elongated trough or hopper 41 and respectively leading into cylindrical chambers 42 formed in line with the openings into the ends of the retorts. Plungers 43 are respectively slideable within these chambers, and for actuating them I provide a shaft 44 mounted in suitable bearings carried by the rear of the stoker casing. Fixed to said shaft are a number of worms 45, respectively engaging worm wheels 46 fixed on short vertical spindles carried in suitable bearings on the stoker frame and each having fixed to its lower end a crank 47. Each crank in turn is connected to its plunger 43 by a connecting rod 48.

Each plunger also has connected to it a pair of parallel connecting rods 48^a and on each of these are mounted two pairs of collars 49 and 50, all of which may be adjusted to vary their positions on said shaft. Between each two collars 49 is slidably mounted a cross head 51 connected through a link 52 with a lug 53 attached to and forming part of the adjacent retort pusher 11. Likewise between the two collars 50 is slidably mounted a cross head 54 connected through a rod 55 with the frame 26, on which are mounted the various twyers 27.

In the present instance the bottoms of the various wind boxes are formed by hinged plates 56 which when closed all lie in approximately the same plane and completely shut off the flow of air to the wind box although when swung down they may permit the flow of any desired quantity of air into said boxes and twyers, it being understood that in the present instance the stoker is designed for operation under induced draft, although, if desired, it may be employed under forced draft, in which case the bottom plates 56 would be closed as shown in the drawings and the various wind boxes

supplied with air from any desired or suitable source.

A sheet metal casing 57 is mounted below the twyers 27 and is supported at the front end of the fire box between the transverse frame member 5 and the lower edge of the boiler plate 1 adjacent the frame member 58 and this casing is provided with bottom doors 59 pivoted to the front and rear bottom edges of the casing and held closed in any desired manner.

Under conditions of operation the shaft 44 is driven by a suitable source of power while fuel is supplied to the hopper 41, and as a consequence the reciprocation of the plungers 43 intermittently forces charges of such fuel into the fire box through the several retorts, so that it passes over the dead plates 25 on to the pusher plates 11 which are reciprocated through the rods 48^a and the connecting rods 52. Obviously the collars 49 may be set on these rods 48^a to give the several pusher plates 11 any desired stroke and in any event, the continued supply of fuel causes it to fill the retorts and fall in front of the various abutments provided by the shoulders 12 and the abutment plates 20. The sliding of the pusher plates thus aids in carrying the fuel to the front of the fire-box to an extent which is in a large measure dependent upon the height to which the abutment plates 20 are raised.

The fuel being ignited, is supplied with air in quantities dependent upon the adjustment of the bottom doors 56, and under operating conditions there is a continuous bed of burning fuel supported upon legs of fuel extending up from the retorts. While the top surface of this fuel bed is substantially horizontal, it may in some cases be inclined upwardly from the rear, to the front of the fire-box, and as the fuel approaches the inner end of the stoker its volume is diminished by reason of the combustion, so that when it reaches the innermost of the twyers 8 but a small portion remains to be consumed. It is, however, gradually delivered onto the inclined series of twyers 27 where the last remnant of the combustible material is burnt, finally falling as ash upon the grate 30, which may be partially opened so that some of it will fall immediately into the casing 57. Any clinkers which are delivered from the furnace collect upon the grate 30, from which they may be dumped from time to time, by operation of the toothed segment 31 through the shaft 33 and hand-wheel 36.

I claim:—

1. The combination in a stoker of structures spaced apart to form retorts; an elongated plate mounted in each of said retorts to form the bottom thereof and provided with openings; pushers pivotally carried by said plate and projecting upwardly through said openings; an arm connected to each

pusher; links connecting the arms; a toothed segment connected to the links; a worm operative on said segment; and means for turning the worm to vary the position of 5 said pushers; with a device for reciprocating the pusher-carrying plates.

2. The combination in a stoker of a series of structures spaced apart to form retorts; reciprocable plates forming the bottoms of 10 said retorts and inclined upwardly toward their inner ends; a series of pushers mounted on each of said plates and formed with fuel-engaging faces of progressively increasing area; arms connected to said pushers respectively of lengths increasing from the inner 15 to the outer ends of the reciprocable plates; and means for simultaneously adjusting said pushers to vary the projection of the pushers above their plates.

20 3. In an underfeed-furnace stoker construction, the combination of a fuel-retort having a movable wall, means to reciprocate said wall, a fuel-pusher adapted to travel with said wall and remain fixed in position 25 relative thereto during the movements of the wall, and means to adjust the position of said pusher relatively to said wall to regulate the feed of fuel without modifying the action of said wall-reciprocating means, 30 substantially as described.

4. In an underfeed-furnace stoker construction, the combination of a fuel-retort having a sliding floor, means to reciprocate said floor, a fuel pusher adapted to travel 35 with said floor, and remain fixed in position relative thereto during the movements of the floor, and means carried by said floor to adjust the position of said pusher relative to said floor to regulate the feed of fuel without 40 modifying the action of said floor-reciprocating means, substantially as described.

5. In an underfeed-furnace stoker construction, the combination of a fuel-retort 45 having its floor and portions of its side-walls slidable, means to reciprocate said floor and side-wall portions, a fuel-pusher adapted to travel with said floor and side-wall portions and remain fixed in position relative thereto 50 during the movements of the floor, and means to adjust the position of said pusher

relatively to said floor to regulate the feed of fuel without modifying the action of said floor-reciprocating means, substantially as described.

55

6. In an underfeed-furnace stoker construction, the combination of a fuel-retort having a sliding wall, means to reciprocate said wall, a fuel-pusher adapted to travel with said wall and remain fixed in position 60 relative thereto during the movements of the wall, said pusher having a slightly inclined top face and an abrupt rear face, and means to adjust the position of said pusher relatively to said wall to regulate the feed 65 of fuel by exposing more or less of said abrupt face to act on the fuel, without modifying the action of said wall-reciprocating means, substantially as described.

70

7. In an underfeed-furnace stoker construction, the combination of a fuel-retort having a recessed slideable wall, means to reciprocate said wall, a fuel-pusher accommodated in said recess, adapted to travel with said wall, and remain fixed in position relative thereto during the movements of the wall, and means to adjust the position of said pusher in said recess to vary the extent of its projection into the retort to regulate the feed of fuel without modifying the action 75 of said wall-reciprocating means, substantially as described.

80

8. In an underfeed-furnace stoker construction, the combination of a fuel-retort having a slideable wall, means to reciprocate 85 said wall, a fuel-pusher carried by the wall, disposed transversely of the direction of travel of the wall, and adapted to remain fixed in position relative to the wall during the movements of the wall, and means to 90 turn the pusher about its axis to adjust its position to regulate the fuel-feed without modifying the action of said wall-reciprocating means, substantially as described.

85

In testimony whereof, I have signed my 95 name to this specification, in the presence of two subscribing witnesses.

MAXWELL ALPERN.
